United States Patent Office

Des. 219,913
Patented Feb. 16, 1971

219,913

TOOL BOX

Howard R. Malm and Grace M. Malm, both of 3907 65th
St., Sacramento, Calif. 95820

Filed Nov. 17, 1969, Ser. No. 20,122

Term of patent 7 years

Int. Cl. D12—14

U.S. Cl. D14—3

FIG. 5

FIG. 4

FIG. 1 is a perspective view of a tool box showing our new design;

FIG. 2 is a front elevational view, the elevational view of the rear being substantially similar except for the drawer handles;

FIG. 3 is an elevational view of one end, the elevational view of the other end being substantially similar;

FIG. 4 is a top plan view; and

FIG. 5 is a view comparable to FIG. 1 but with the tool box in open position.

We claim:

The ornamental design for a tool box, as shown and described.
